The ornamental design for a ribbon measuring tool, as shown and described.

DESCRIPTION

FIG. 1 is a perspective view of the ribbon measuring tool in an extended configuration.

FIG. 2 is a top view of the ribbon measuring tool of FIG. 1. FIG. 3 is a bottom view of the ribbon measuring tool of FIG. 1.

FIG. 4 is a side view of the ribbon measuring tool of FIG. 1, the opposite side is a mirror image.

FIG. 5 is an end view of the ribbon measuring tool of FIG. 1, the opposite end is a mirror image.

FIG. 6 is a perspective view of the ribbon measuring tool of FIG. 1 in a collapsed configuration.

FIG. 7 is a top view of the ribbon measuring tool of FIG. 6. FIG. 8 is a bottom view of the ribbon measuring tool of FIG. 6.

FIG. 9 is a side view of the ribbon measuring tool of FIG. 6, the opposite side is a mirror image.

FIG. 10 is an end view of the ribbon measuring tool of FIG. 6, the opposite end is a mirror image; and,

FIG. 11 is an exploded perspective view of the ribbon measuring tool of FIG. 1.
